MAGNET OPERATOR STRUCTURE

John C. Ponstingl, Pittsburgh, Pa., assignor to Westinghouse Electric Corporation, East Pittsburgh, Pa., a corporation of Pennsylvania

Application July 22, 1948, Serial No. 40,087

5 Claims. (Cl. 74—579)

1

My invention relates to electromagnetically operable switches and more particularly to the supporting and operating elements for the movable armature of such switches.

A broad object of my invention is the provision of a simple, rugged, reliable, and inexpensive operator for an electromagnetically actuated device.

A still broader object of my invention is the provision of improved operator elements for an electromagnetic device as a switch.

A more specific object of my invention is the provision of an extremely rugged and simple operator frame consisting of two identically shaped elements suitably secured to each other.

Other objects and advantages will become more apparent from a study of the specification and the accompanying drawing, in which:

Figure 1 is a side view of one half of an operator for an electromagnetic device;

Fig. 2 is a view from the rear of the subject matter shown in Fig. 1;

Fig. 3 is a top plan view of one of the elements such as shown in Fig. 1;

Fig. 4 is a view from below of the same type element shown in Fig. 1;

Fig. 5 shows a side view of the elements, shown in Figs. 3 and 4, in assembled relation;

Fig. 6 shows a view from the rear of the subject matter shown in Fig. 5;

Fig. 7 shows the bottom portion of Fig. 6 in vertical section; and

Fig. 8 shows the elements shown in Fig. 5 in assembled relation with the other elements of a complete electromagnetic switch operator.

In Fig. 8 of the drawing, 1 designates the base or control panel to which my device, in use, is secured. The E-shaped magnet 2 is provided with a pair of heavy laminations 3 on its outer surfaces. These laminations are provided with flanges 4 at the rear for mounting the magnet 2 to the base 1.

The magnet structure is so mounted on the base 1 that the open part of the E faces downwardly, that is, the legs 6, 7 and 8 are directed down and with the stem 9 being disposed so as to project horizontally from the base.

The middle leg 1, or core, carries the energizing coil 10 held in place by friction or some simple readily displaceable coil holding means, as spring 5, constituting no part of my invention.

To the forward leg 6, I secure the generally rectangular plate 11. This plate 11 is provided with tabs, or tongues 12 and 13 that project beyond the upper surface of the stem 9 and the

lower surface of the armature 14. These tabs are slightly under-cut at the junction of the tab with the main portion of the rectangular plate. The amount of under-cut is such that the frames 15 and 16 can not be removed without compressing the springs 17 and 18 which are disposed between the tab 12 and projection 131 and tab 13 and projection 31, respectively.

The discussion of Fig. 8, and with reference to the elements from 1 to 18 inclusive, is merely first here given to properly show the environment of my invention, but does not disclose my invention in detail. My invention in this application is confined to the operator frame that is actuated by the armature 14 upon energization of coil 10.

The operator frame 21, shown complete and separate from its environment in use in Figs. 5 and 6, consists of two pieces 22 and 122 spot-welded into a unitary rigid and simple frame by the spot welds at 54, 55, 56 and 57. Each of the pieces 22 and 122 is stamped from flat material by the use of a single die. The pieces, even after complete shaping, are thus identical in shape.

As viewed from the side it will be noted that the piece 22 is generally in the shape of a square C or a U disposed on its side. The upper leg 24 is provided with a foot 25 disposed in the same plane as the leg 24 but disposed at right angles to the leg 24. The foot 25 is provided with a toe 26 bent at right angles to the foot 25. Further the toe is provided with an apertured forwardly directed projection 27. The parts to be actuated by the operator are secured to the projection 27.

The lower leg 28 is provided with a foot 29 disposed in the same plane as leg 28 but disposed at right angles to the leg 28. The foot 29 is provided with a toe 30 bent at right angles to the foot 29. The toe is provided with a dove-tailed projection 31 projecting at right angles to both the leg 28 and toe 30.

From some of the figures in the drawing, it will be apparent that the piece 122 is also generally in the shape of a square C, or a U disposed on its side. The lower leg 124 is provided with a foot 125 disposed in the same plane as the leg 124 but disposed at right angles to the leg 124. The foot 125 is provided with a toe 126 bent at right angles to the foot 125. Further, the toe 126 is provided with an apertured forwardly directed projection 127. Parts to be actuated by the operator 21 may be secured to this projection.

The upper leg 128 is provided with a foot 129 disposed in the same plane as the leg 128 but dis-

posed at right angles to the leg 128. The foot 129 is provided with a toe 130 bent at right angles to the foot 129. The toe 130 is provided with a projection 131, in the shape of a dove-tail, projecting at right angles to both the leg 128 and the toe 130.

In building my operator I take the pieces just described, retain one in the position shown in Fig. 2 and turn the second piece, while in the position shown in Fig. 2, through an angle of 180° in a clockwise direction and then interfit the parts as shown in Fig. 6. During stamping the toe 30 is provided with the two spaced pips 32 and 33 and the toe 26 is provided with the holes 34 and 35. The toe 130 is similarly provided with pips 132 and 133 and the toe 126 is similarly provided with the holes 134 and 135. In assembling the two pieces 22 and 122, the pip 32 of piece 22 is made to fit into the opening, or hole, 135 of the piece 122 and the pip 33 of piece 22 is made to fit into the hole 134 of piece 122. Similarly, the pips 132 and 133 on the piece 122 are made to interfit with the holes 34 and 35, respectively, on piece 22. These pips and holes thus provide guiding means to insure correct positioning or alignment of the two pieces 22 and 122 on each other. Assembly is thus facilitated by spot welding at the pips, as indicated at 54, 55, 56 and 57, the rigid unitary structure shown in Fig. 6 is provided.

The operator 21 is then provided with the bearing sleeves 40 and 41. These bearing sleeves provide the bearings for the armature 14.

A study of Figs. 6 and 8 will show that the assembled operator 21 provides the right-hand side or portion of a parallelogram construction with the plate 11 forming the left-hand side. The frames 15 and 16 and the springs 17 and 18 thus form the end portions of the parallelogram construction.

The tabs 12 and 13 have a construction, or shape, similar to the projections 31 and 131. The frames 15 and 16 are generally in the shape of a picture frame but with the end portions beveled inwardly. The frames are thus latched in position when the springs 17 and 18 are in expanded position as shown in Fig. 8.

To better understand the utility and function of the operator, reference may be had to the structure and function of the parts associated with the compression springs 17 and 18.

Since the compression spring 17 is at its ends held in place by the buttons 12' on the tab 12 and the projection 131, respectively, it is apparent that the spring holds the frame 15 under tension.

The compression spring 18, coacting similarly with the buttons 13' on the tab 13 and the projection 31, respectively, holds the frame 18 under tension. Since the tabs 12 and 13 are on the ends of the plate 11 and the bight portions of the pieces 22 and 122 are guided by the plate 11, the operator is free to move vertically upon actuation of the armature 14 by the energization of the coil 10. Suitable electric contacts, or switch members may thus be actuated by the operator frame 21.

My invention is broader in scope than the single showing made. I, therefore, do not wish to be limited to the single showing made but wish to be limited only by the scope of the claims hereto appended.

I claim as my invention:

1. An operator frame for an electromagnetically actuated switch, in combination, a first side

member in the shape of a square C, a first foot at the upper leg of the C, a second foot at the lower leg of the C, a first toe element projecting from the first foot, a second toe element projecting from the second foot, and a flat member projecting at right angles from the second toe element, and a second side member like the first turned end for end disposed on the first side member so that the flat member of the first side member hooks over the second toe element on the second side member and the flat member of the second side member hooks over the first toe element on the first side member, one of said toe elements being provided with spaced projections and the toe element disposed in contiguous relation having holes spaced to receive the projections whereby assembly of the side members is facilitated.

2. An operator frame for actuation by an armature of an electromagnetic device, in combination, a flat one-piece first side member generally in the shape of a square C thus having two legs, a foot at the end of each leg, a first toe element disposed at right angles to one foot, a second toe element disposed at right angles to the other foot, a projection disposed at right angles to the second toe element, and a second side member like the first side member disposed on the first side member so that the first toe element of the second side member rests at the inside corner formed by the projection and second toe element on the first side member, and the first toe element on the first side member rests at the inside corner formed by the projection and second toe element on the second side member.

3. An operator frame for the elements to be operated by the movement of an armature of an electromagnetic device, in combination, a first side member stamped from flat sheet metal so as to be generally in the shape of a square C to thus have an upper leg and a lower leg, a foot at the upper leg in the plane of the upper leg projecting upwardly from the upper leg, a foot at the lower leg in the plane of the lower leg projecting downwardly from the lower leg, a first toe element on the upper foot projecting at right angles from the plane of the foot, a second toe element on the lower foot projecting at right angles from the plane of the foot, a projection on the second toe element projecting at right angles from the toe element at the edge nearer the bight of the C, and a second side member like the first in every detail turned end for end on an axis falling in the plane of the side member disposed on the first side member so that the outside surface of the first toe element of the first member is in contiguous relation to the inside surface of the second toe element of the second member, and the inside surface of the second toe element of the first member is in contiguous relation to the outside surface of the first toe element of the second member, and means for securing the toe elements to each other, whereby the second side member is secured to the first side member.

4. An operator frame for the elements to be operated by the movement of an armature of an electromagnetic device, in combination, a first side member stamped from flat sheet metal so as to be generally in the shape of a square C to thus have an upper leg and a lower leg, a foot at the upper leg in the plane of the upper leg projecting upwardly from the upper leg, a foot

at the lower leg in the plane of the lower leg projecting downwardly from the lower leg, a first toe element on the upper foot projecting at right angles from the plane of the foot, a second toe element on the lower foot projecting at right angles from the plane of the foot, a projection on the second toe element projecting at right angles from the toe element at the edge nearer the bight of the C, said toe element on the lower foot being provided with a pair of upwardly directed spaced projections, said toe element on the upper foot being provided with a pair of openings aligned and sized to match the projections, and a second side member like the first in every detail turned end for end so that the bight of the C of the second side member is beside the bight of the C of the first side member and the two side members fit onto each other so that the projections on one fit into the openings of the other.

5. An operator frame for the elements to be operated by the movement of an armature of an electromagnetic device, in combination, a first side member stamped from flat sheet metal so as to be generally in the shape of a square C to thus have an upper leg and a lower leg, a foot at the upper leg in the plane of the upper leg projecting upwardly from the upper leg, a foot at the lower leg in the plane of the lower leg projecting downwardly from the lower leg, a first toe element on the upper foot projecting at right angles from the plane of the foot, a second toe element on the lower foot projecting at right

angles from the plane of the foot, a second side member, similar in structure to the first side member, disposed on the first side member so that the top surface of the upper toe element of the first side member is in contiguous relation to the bottom surface of the top toe element of the second side member and the top surface of the bottom toe element of the first side member is in contiguous relation to the bottom surface of the bottom toe element of the second side member, and means for rigidly securing the side members to each other at the contiguous surfaces of the toe elements.
